**MILL'S COLOSSEAN EQUESTRIAN STATUE
or GENERAL ANDREW JACKSON**

Dedicated to the American Army and the People of the United States by the Public

Ms. 704

Clark Mills of Washington D. C.
Letter Patent No. 704 Dated May 15th 1855

The Schedule referred to in these Letters Patent making part of the same

To all whom it may concern

Be it known that I Clark Mills
^{in the County of Washington} and District of Columbia have invented or produced
a new and original design for an Equestrian Statue, and I do hereby
declare the following is full clear and exact description of the same
reference being had to the accompanying drawing making part thereof,
and which represents a perspective view of the statue in question.

The nature of my design relates to an equestrian statue
in which the horse is rampant, and so poised as to be supported
on his hind legs only, and mounted by a rider, as seen in the
drawings

A. represents a base or stand upon which the hind legs
C. of the horse are imbedded or otherwise secured so as to avoid all other
artificial supports which detract from the general effect of the statue

104
154

Des. 704

B represents the horse in a rampant position with a flowing tail D, and upon said horse is mounted a rider C in military with the reins F grasped in his left hand, and Chapeau G. in his right hand. The trappings being of a character suited to the special design, and the size of the whole depending upon the fancy of the maker or user.

The general configuration of the design is such as represented in the drawing, and it may be placed on a pedestal or not as may suit the circumstances of the case.

Having thus explained the general characteristics and configuration of my new and original design what I claim therein as new and desire to secure by Letters Patent is a design for an Equestrian Statue such as represented
